ABSTRACT

A process for forming a picture image employing a transfer material which retains a powder image and an image receiving member. The two members are brought into close contact with each other to effect transfer of the powder image by means of electrostatic force. Magnetic materials are employed in or on the back sides of the transfer member and the image receiving member creating a magnetic attractive force between the magnetic materials so as to bring the powder image surface of the transfer member into close contact with the image receiving member resulting in an effective transfer of the powder image.

METHOD FOR FORMING A PICTURE IMAGE

BACKGROUND OF THE INVENTION

This invention relates to a method for forming a picture image and more particularly to a method of obtaining a transfer picture image.

Previous methods practiced in the prior art to transfer images include contact transfer processes wherein a transfer material is brought into close contact with an image receiving material for transferring a picture image to the latter. In order to obtain a picture image of sufficiently good quality employing this contact copying process, an original picture on a transfer material and a surface of an image receiving material must be brought into close and uniform contact with one another. With this view in mind achieving uniform intimate contact has been attempted between these members employing mechanical pressure, a vacuum force and electrostatic forces which are conventionally resorted to.

Mechanical pressure can be obtained with relative ease to supply uniform layer or point contact but it is not convenient for the purpose of bringing surfaces into closing uniform contact by reason of the difficulties in applying uniform pressure to a plane. Vacuum forces when applied invariably results in an increased size of the apparatus and complexity of its construction producing other noticeable and substantial disadvantages. When employing electrostatic force it is desirable that the apparatus for achieving surface contact may be made small in size and simple in construction. However, this method is employed for a contact copying process, wherein difficulties are encountered in transferring a toner electrostatically retained on a transfer medium to an image receiving material surface forming a picture image since an electric field several to several tens of times greater than that conventionally employed for producing an electrostatic force is required in order to retain the toner for producing an electrostatic force to bring the two materials into sufficiently close contact with one another. Due to this strong electric field that is required, the toner is transferred to the image receiving material prematurely before close contact is achieved.

There is therefore, a demonstrated continuing need for improved methods of imaged transfer from an image retaining member or transfer member to an image receiving member.

It is, therefore, an object of this invention to provide a method which is devoid of the above noted deficiencies.

It is a further object of this invention to provide a novel image transfer process.

Another object of this invention is to provide a novel transfer copying process which employs a transfer material employing both conductive and non-conductive surfaces in order to provide both a toner image and a means to transfer the toner image to an image receiving member.

It is a further object of this invention to provide a method which results in sufficiently good quality in contact copying processes by allowing an original picture image on a transfer member and a surface of an image receiving member to be brought into close and uniform contact one with the other.

These and other objects are accomplished generally speaking by providing a process for forming an image

wherein a transfer member retaining a powder image thereon and an image receiving member are brought into close contact with each other for effecting transfer of the powder image by means of electrostatic force.

5 Magnetic material is provided in or on the back sides of the transfer material and the image receiving member creating a magnetic attractive force between the magnetic materials thus bringing the powder image carrying surface of the transfer member into close contact with the image receiving member surface so that the powder image may be transferred by electrostatic attraction.

This novel transfer copying process employs a transfer material comprising a nonconductive substrate and 15 a conductive layer provided on one surface thereof which process comprises removing the conductive layer in an imagewise pattern thereby exposing the nonconductive image areas, and powder in the resulting group portions to form an original picture image 20 and transferring the material image to an image receiving member by electric or other suitable means to form a transferred picture image. More specifically a method for forming a picture image is provided wherein a transfer member retaining a powder image thereon and an 25 image receiving member are brought into close contact with each other for transferring the powder image onto the image receiving member by means of electrostatic force. The method comprises uniformly dispersing magnetized material in at least either of the transferring 30 member or the image receiving member for cooperation with another magnetic material in the other member to effect close contact of the powder image retaining surface and a transfer material so as to result in transfer of the powder image by electrostatically applied force.

The transfer member may be comprised of any suitable nonconductive material. Typical nonconductive materials include resin films, such as polyethylene, polyvinylchloride, polystyrene, polyester, 40 polyvinylidenechloride and paper impregnated with silicone, an alkyd phenol resin or an epoxy resin for insulation purposes. Substrates employed should desirably have a resistance of over 10^{12} ohms/cm.

The transfer member may be comprised of any suitable conductive layer. Typical conductive layers include, resins which contain disperse conductive particles, a vapor evaporated metal film, a plated metal film membrane, a conductive resin or the like all of which are easily removable. Easily removable for the purposes of the present invention is defined as locally removably by means of a steel pen, a writing device for scribe-recording and the like. The conductive layer employed should desirably have a resistance of less than 45 10^{10} ohm/cm.

55 Any suitable image receiving material may be employed in the process of the instant invention. Typical image receiving materials include, cooper plate, iron plate, zinc coated iron plate, and tin coated iron plate. A thin non-magnetic material lined with a strong magnetic material may also be employed as the image receiving material.

Any suitable toner may be employed in the process of the instant invention. It is preferable that a toner with a particle size and a range of 3-30 microns be conveniently employed for use in copying. At the same time the maximum number of powder layers embedded in a groove portion of the original picture image may

be expressed as (a depth of the groove a particle diameter of charged powder). Based on the assumption that a transfer efficiency of 80-90% is required to achieve a sufficient density which depends on developed mass and transfer efficiency not transfer efficiency alone, of a transferred image it may be concluded that a required number of powder layers in the groove portion is over 3-5. For these considerations a desirable depth of the groove may be calculated to be over 10 microns. Of course a groove depth depends on the color and the condition of the surface and the color of the toner.

Any suitable magnetic material may be employed in the process of the instant invention. Typical magnetic materials include strongly magnetic material powder dispersed in a resin binder including barium ferrite, cobalt ferrite, nickel ferrite among others. Any suitable resin binder may be employed in the process of the instant invention in connection with the magnetic particles described above. Typical binders include, acrylic resin, alkyd resin, butadiene-acrylonitrile rubber, butadiene-styrene rubber, natural rubber, silicon rubber, ABS resin, and styrene resin.

A contact plate containing a magnetized magnetic material may be placed on the image receiving member. A strong magnetic attraction occurs between the contact plate and the image receiving member, the transfer member being disposed there between this achieving close intimate contact between the transfer member and the image receiving member. Any suitable contact plate as described above may be employed in the process of the instant invention. Normally a magnetic material magnetized to holding a force of over 1 gm/cm³ or desirably 5 gm/cm³ is employed in one of the following arrangements:

1. the contact plate is nonconductive in its entirety;
2. the contact plate has a multiple-layer structure with a conductive and nonconductive layers; or
3. the contact plate is conductive in its entirety.

Where the contact plate is of type 2 it suffices if either a nonconductive layer or a conductive layer comprises a magnetized material. Of course, both layers may include a magnetized material. When the contact plate is of either of type 1 or 2 the corona charging device applies a corona ion having the same polarity as the toner onto the back surface of the contact plate to transfer the toner image onto the grounded image receiving material. When the construction of the plate is of either of type 1 or 2 the nonconductive portion thereof should desirably have a surface and a volume resistance over 10¹² ohms. This is to preclude leaking of the charge through the nonconductive portion.

If the nonconductive portion is excessively thick, its electrostatic capacity contributes to diminishing the electric field which serves to transfer the toner image deposited in the portion of the transfer member onto the image receiving member thus yielding an undesirable result. Thus, it is found that the thickness of the nonconducting portion is desirably to be kept under 5 mm. When the contact plate is of type 2 or 3 its conductive portion may be electrically floated while applying corona ion by a corona charging device on the contact plate from above to achieve relocation of the toner image on the image receiving member. In the event the construction of the contact plate is of type 2 or 3 furthermore, a voltage may also be applied between the conductive portion thereof and the image re-

ceiving member to cause relocation of the toner image on the latter.

The general objects and advantages of the instant invention having been discussed, the specifics of the instant invention will be more readily understood with reference to the following drawings of which:

FIG. 1 illustrates an example of an transfer material for use in the process of the instant invention.

FIG. 2a illustrates a transfer material of FIG. 1 with 10 a conductive layer removed in an imagewise pattern.

FIG. 2b illustrates the member of 2a placed onto a grounded substrate with corona charging supplied.

FIG. 2c illustrates the member of 2b with toner applied.

15 In FIG. 2d is seen the image receiving member of FIG. 2c placed on an image receiving member containing a highly magnetic material with a contact plate placed behind the imaged transfer member.

20 In FIG. 3 there is illustrated another embodiment of the instant invention wherein an imaged receiving member possesses a curvature.

25 In FIG. 4 still another embodiment of the instant invention is illustrated which includes a transfer member for use in the present invention comprising a support which is flexible and di-electric in nature, an exfoliating layer provided on the support and an easily removable conductive layer provided on the exfoliating layer.

30 In FIG. 5 there is seen another embodiment of a transfer member comprising a support an easily removable conductive layer provided on a front surface of the support and a magnetized magnetic material layer provided on the back surface of the support.

35 In FIG. 6 there is seen another embodiment of the instant invention wherein a magnetic body which is provided substantially evenly onto a back surface of a supporting body of a transfer member in form of islands, stripes or a grill pattern is provided.

40 In FIG. 1 is shown one embodiment of a transfer member for use in the process of the instant invention. Number 1 denotes a transfer material comprising a plastic and nonconductive substrate to having an easily removable conductive layer 3 provided thereon. The conductive layer 3 is made of a resin which contains dispersed conductive particles, as described above.

45 In FIG. 2a is seen the transfer member 1 of FIG. 1 with the conductive layer 3 removed in an imagewise pattern by means of a steel pen, a writing device for scribe-recording and the like. 4 denotes a picture image region at which the nonconductive supporting body 2 surface is exposed by the removal of the conductive layer. Thus, the transfer member 1 is given both the ability to retain a picture image information and the ability to transmit or transfer the information. This portion from which conductivity is removed is an image-wise pattern, may be made conductive again by covering same with, for instance, a conductive ink, thus facilitating correction or modification.

50 In FIG. 2b, as seen, the supporting body 2 which is placed on a grounded substrate plate 5, and corona charging is effected from the side of the conductive layer 3. In the FIG. 6 denotes a corona charger 7 a high voltage source for supplying a high voltage to the corona charger 6, and 8 a charge deposited on the non-conductive surface of an exposed portion 4 where the conductive layer is removed in an imagewise pattern. Here, the conductive layer 3 may be grounded simultaneously with or subsequent to the charging. In neither

case is the charge retained on the conductive layer 3.

In FIG. 2c a powder material hereinafter referred to as toner, having a charge opposite in polarity to that of the charge 8 is supplied onto the picture image region 4 having the charge 8 thereon, thereby carrying out development. The toner is deposited only in the picture image region 4 due to electrostatic force, forming an image 9. Any of conventional electrophotographic dry developing methods including cascade method, powder cloud method, magnetic brush method, and fur bush method may be used for the purpose of developing. Transfer member 1 having the toner image 9 formed thereon is placed onto an image receiving material 10 containing a highly magnetic material, in such a manner that the toner image is in contact with the image receiving, as shown particularly in FIG. 2d. Suitable materials for use as the image receiving member 10 are described above. A strong magnetic attraction occurs between the contact plate 11 and the image receiving material 10 the transfer member 1 being disposed and held between the contact plate and the image receiving material to achieve close intimate contact between the transfer member and the image receiving member 10. 7 denotes a high DC voltage source, and 12 a charge applied onto the back surface of the contact plate 11.

In FIG. 3 is illustrated still another embodiment of the instant invention wherein an image receiving member possesses a curvature. Number 10 denotes an image receiving member comprising a strong magnetic layer with curvature in the form of a cylindrical shape. A transfer material 1 carrying a charged powder image 9 on picture image portions thereof is placed onto an image receiving material 10 in such a manner that the side of the conductive layer 3 of the transfer material 1 is brought into face-to-face contact with the image receiving material 10. On the transfer member 1 furthermore there is superimposed a contact plate 11 comprising a flexible magnetized strongly magnetic material. The contact plate 11 by means of a strong magnetic attractive force causes the transfer material 1 to sit intimately over the image receiving material 10 along the curved surface thereof achieving good contact between the transfer material 1 and image receiving member 10.

In FIG. 4 still another illustration of the transfer member for use in the present invention. A transfer member 1 comprises a support 2 which is flexible and dielectric in nature, an exfoliating layer 14 provided under support 2 and an easily removable conductive layer 3 provided on the exfoliating layer 14. This embodiment has the advantage in that a grooved picture image can be obtained without making the conductive layer 3 very thick. This embodiment illustrates a transfer member for transferring a powder image as used in the methods of this invention particularly shown in FIGS. 2-4. Materials for use in the support 2 in the conductive layer 3 are the same as hereinbefore described. The image receiving member as illustrated in the form of cylindrical shape. It should be apparent however, that the shape equally may be columnar, spherical, wavy, or the like. When the image receiving member is a spherical, mountainlike or conical form with a radius of extremely small curvature, however, it is necessary that the transfer member and the contact plate are also formed into a shape corresponding to that of the image receiving member. Materials for use as the transfer material 10 and the contact plate 11 are the same as those

used in the case shown in FIGS. 2 except that the contact plate 11 must be of a flexible material in this embodiment.

In FIG. 5 a transfer material 1 comprising a support 2 an easily removable conductive layer 3 provided on the front surface of the support 2 and a magnetized magnetic material layer 15 provided on a back surface of the support 2 is seen. The magnetic material layer is comprised of strongly magnetic material powder dispersed in a resin binder.

In FIG. 6 is seen a magnetic body 16 which is provided substantially evenly onto a back surface of a support 2 of a transfer material 1 in the form of island stripes or a grill pattern. This magnetic layer 16 may be formed, for instance, by applying an ink-like solution of magnetic powder and a resin binder, which are dissolved in a solvent, by means of a gravure method. The magnetic layer 16 may be formed by any desired conventional method.

To further define the specifics of the present invention the following examples are intended to illustrate and not limit the particulars of the present system. Parts and percentages are by weight unless otherwise specified.

EXAMPLE I

A conductive layer is applied to a dry thickness of 3 microns comprising the composition given below to a support of 100 microns thick polyethylene terephthalate film. The conductive layer possesses a resistance of 10³ ohm/cm.

35	Styresol No. 4250, a styrenated alkyd resin	1 part by weight
	carbon black	4 parts by weight
	Toluene	8 parts by weight

40 Employing a steel pen, the conductive layer of the transfer member is removed to expose a nonconductive surface in an imagewise pattern. The transfer member is placed onto a grounded conductive substrate plate in such a manner that the film support of the transfer member is superposed on the substrate plate. The conductive layer is grounded and is charged by a corona charging device to which a DC voltage of +5 kv is imposed. The charge is retained at picture image regions, namely, at the regions where the nonconductive film support surface is exposed. At the nonpicture image regions, that is, at the conductive layer, the charge is leaked out to the ground, thereby forming a charged image corresponding to the pattern of the picture image region. The conductive layer side of the transfer member is subsequently developed by a cascade developer with negatively charged toner. Toner is deposited at the region of the charged image thus forming a toner image. The transfer member is placed onto an image receiving member comprising a grounded iron plate of 10 mm thickness in such a manner that the toner image surface, that is, the conductive layer side, of the transfer member is held in face-to-face contact with the iron plate. Furthermore, a magnetized rubber magnet sheet of 0.8 mm thickness having a coercive force of 13 g/cm³ is placed over the transfer member. The transfer member is sandwiched between this rubber magnet sheet and the iron plate. This rubber magnet sheet possesses

a resistance of greater than 10^{15} ohm/cm and is thus nonconductive.

A negative charge is then applied to the conductive layer from a rubber magnet surface side by means of a corona charger, to which is imposed a DC voltage of -8 kv. Consequently, the toner image which is deposited at the imagewise grooved portions of the transfer member is transferred onto the iron plate surface. After separating the transfer material from the iron plate the transferred toner image on the iron plate is fixed by tri-chloroethylene spraying.

EXAMPLE II

A contact plate is employed having the same rubber magnet as described in Example I on one surface of which is adhered a 20 micron thick aluminum foil by means of an epoxy-base adhesive. A 10 mm-thick iron plate is used as an image receiving member as in Example I onto which an iron plate is placed on the transfer material in such a manner that a toner image surface, that is a conductive surface, of the transfer member is brought into face-to-face contact with the iron plate. Furthermore, onto the transfer material is placed the contact plate with the aluminum surface thereof being held in face-to-face contact with the former. A DC voltage of 1 kv is then imposed between the aluminum layer of the contact plate and the iron plate. As a result, the toner image is successfully transferred onto the iron plate surface.

EXAMPLE III

A triacetylcellulose film of 100 micron thickness is used as an image receiving member. This film is onto an iron plate of 10 mm thickness, on which film is placed a transfer member in the same manner as in Example I. Furthermore, a rubber magnet sheet is superposed on the transfer member to bring the transfer member into close contact with the image receiving material by means of a magnetic force. Corona charging is carried out in the same manner as in Example I to obtain a good picture image of the triacetylcellulose film.

EXAMPLE IV

A triacetylcellulose film of 50 micron thickness is used as support, which film is coated with a dispersion of the following composition to form a conductive layer of 20 micron dry thickness.

carbon black	25 parts by weight
nitrocellulose	3 parts by weight
castor oil	1 part by weight
alcohol	150 parts by weight
ethyl ether	200 parts by weight
acetone	10 parts by weight

The resistance of this conductive layer is approximately 10^6 ohm/cm. The conductive layer of the transfer material is removed by a scribe recording needle thereby exposing the support surfaces and forming grooves at the picture image portions. This transfer material is electrically charged and then developed by a toner as in Example I. The toner is embedded in the grooved nonconductive picture image regions. The toner image is placed onto a shot-blasted steel plate of 20 mm thickness, simultaneously carrying out position adjustment. The same kind of a magnetized magnetic

material is used in Example I is superposed on the transfer material, and corona charge is applied thereover. Consequently, the toner image is successfully transferred onto the steel plate and furthermore, the resultant toner image is not disturbed. This transferred toner image is fixed in the same manner as in Example I.

EXAMPLE V

Epoxy resin powder having an average particle size of 5 microns is dispersed substantially evenly over a conductive layer side surface of a transfer member carrying thereon the same picture image as in Example IV. The powder on the conductive layer surface is removed by a doctor blade, leaving the powder embedded in the grooved picture image portions only. This recording material is placed onto a grounded conductive substrate plate, to which recording material is applied from the conductive layer side thereof and a corona charge by a conventional corona charging device is imposed at a voltage of -5 kv. The conductive layer is then grounded to remove the charge deposited thereon. The recording material is then subjected to transfer and fixation in the same manner as in Example IV. In the case of this Example, the resultant powder image is not disturbed.

EXAMPLE VI

The same kind of a transfer member as in Example V is subjected to removal of a conductive layer in a picture image pattern in the same manner as in Example V. After charging and developing with toner the transfer material member is placed onto a grounded image receiving member in the form of a tin-plated iron cylinder having a radius of 8cm in such a manner that the powder image surface, that is, the conductive layer surface, of the transfer member is held in face-to-face contact with the image receiving member. Furthermore, a flexible contact plate, similar to that of Example I is suspended over the transfer material in such a manner as to ensure the plate to fit intimately over the circumferential surface of said cylinder in order to achieve good contact with each other. By means of a corona charger operating at a high voltage of -10 kv, a charge is applied substantially uniformly over the contact plate. When the contact plate and the transfer member are separated from the cylinder, the powder image is successfully transferred onto the circumferential surface of the cylinder.

EXAMPLE VII

A transfer material comprising a support of 125 micron thick polyethylene terephthalate film is supplied with a scribe layer of the composition given below having a dry thickness of 12 microns and a conductive layer is provided on the scribe layer. The scribe layer exhibits a suitable brittleness as a result of brushing due to condensation of moisture with rapid evaporation of the solvent during drying. The composition of the scribe layer is as follows:

barium stearate	80 parts by weight
nitrocellulose	70 parts by weight
ethyl cellulose	30 parts by weight
acetone	700 parts by weight
methyl ethyl ketone	150 parts by weight
methanol	200 parts by weight

The scribe layer has a resistance of over 10^{15} ohm/cm, and is thus nonconductive. For a conductive layer, a dispersion solution having a composition similar to the conductive layer of the transfer material of Example I is applied to the scribe layer to a dry layer thickness of approximately 3 microns. When the conductive layer side of the transfer member is scratched in an imaged pattern employing a steel pen, the conductive layer and the scribe layer are removed from the support and the support surface is exposed to form a grooved picture image region. As in Examples IV and V, the position of the transfer member is properly adjusted to that of an image receiving member, and then a contact plate is superposed thereon for carrying out the transfer with a good resulting picture image employing techniques described.

EXAMPLE VIII

A mixture of the following composition is used to form a scribe layer to a dry thickness of 20 microns.

zinc stearate	75 parts by weight
nitrocellulose	120 parts by weight
castor oil	30 parts by weight
methyl acetate	200 parts by weight
acetone	250 parts by weight
methanol	100 parts by weight

During, drying brushing takes place as in Example VII and a suitable layer for scribing is obtained. Onto the scribe layer, a mixture of 80 parts by weight of polyvinyl potassium benzenesulfonate and 20 parts by weight of silica gel, which has been dissolved in water containing a small amount of methanol, is applied to form a conductive layer. The dry thickness of the conductive layer is approximately 2 microns. The layer possesses a resistance of approximately 10^8 ohm/cm. Also, both the scribe layer and the conductive layer are translucent. This facilitates easy positioning of the transfer member and the image receiving member when the transfer is carried out by the methods of Examples VI or V. Consequently a good transferred image is formed on the image receiving member.

EXAMPLE IX

A transfer member is prepared in the same manner as in Example VIII except that 5 parts by weight of Rose Bengal is added to the mixture of Example VII. As a result, a non-picture image portion of this Example becomes pink-tinted translucent, while the picture image portion remains transparent, making it possible to clearly distinguish the picture image portion. The transfer member and the contact plate are independent members. It is possible to integrally combine the transfer material with the plate and if the transfer material itself is a magnetized material, the contact plate becomes unnecessary.

EXAMPLE X

A transfer member is prepared by forming a magnetic material layer of the following composition on the support side of a transfer member similar to that used in Example I so that a dry thickness of a magnetic layer of 50 microns is provided:

barium ferrite	10 parts by weight
styrenated alkyd resin	4 parts by weight
toluene	100 parts by weight

After the conductive layer of the transfer member is removed in an imagewise pattern, barium ferrite powder in the magnetic material layer is magnetized by an electromagnet. Electric charging and powder developing are then carried out in the same manner as in Example I and subsequently the recording material is placed onto a shot-blasted 10 mm-thick steel plate. The recording material is brought into intimate contact with the steel plate surface, followed by corona charging for transfer, as a result of which a powder image is transferred onto the image receiving material to form a good image thereon. When the above process is repeated employing a cylindrical image receiving member, similar effectively good contact is obtained and a powder image is successfully transferred.

EXAMPLE XII

A conductive layer having the same composition as in Example IV is applied onto a commercially available 0.8 mm-thick rubber magnet sheet. The dry thickness of the layer formed is approximately 25 microns. The resulting transfer member is subjected to picture image forming, charging powder developing and transferring with good contact with a cylindrical image receiving member, thereby achieving a successful transfer employing techniques previously outlined in Example XI.

EXAMPLE XII

A transfer member comprising a support of a 50 micron thick polyethylene terephthalate film and a conductive layer, which is obtained by spraying, having a dry thickness of about 50 microns and comprising a mixture of the following composition I prepared:

carbon black	30 parts by weight
cobalt ferrite powder	80 parts by weight
nitrocellulose	10 parts by weight
castor oil	2 parts by weight
alcohol	300 parts by weight
ethyl ether	500 parts by weight
acetone	50 parts by weight

This conductive layer possesses a resistance of approximately 10^8 ohm/cm and is easily removable by means of a steel pen. Using the conductive layer, furthermore a good transferred image is obtained as in Example X. Magnetized magnetic film is provided on the entire surface. It is also possible employing this process to distribute the magnetic materials substantially evenly over the back surface of the support in the form of an island, stripe or grill pattern. This is found to facilitate easy positioning of the transfer member and an image receiving member when the magnetic material is opaque provided the support and the conductive layer are transparent or translucent.

EXAMPLE XIII

Onto the back surface of the support of a transfer member as shown or as described in Example VIII magnetic ink of the following composition is applied in a substantially evenly dispersed island pattern by gravure printing:

EXAMPLE XVI

barium ferrite powder	100 parts by weight
a styrenated alkyd resin	40 parts by weight
linseed oil	10 parts by weight
toluene	60 parts by weight

The islands have a square shape with a dimension of 3mm × 3mm which islands are formed at a distance of 10mm from each other by a continuous pattern. A thickness of the magnetic material layer is approximately 0.2 mm. This recording material is subjected to conductive layer removal magnetization, charging powder developing, and transferring in the same manner as employed in Example X to yield an excellent transferred image. Furthermore, positioning of the recording member and the transfer member during the transfer step are easily carried out.

EXAMPLE XIV

A transfer member comprising a 100 micron thick polyethylene terephthalate resin film and a vacuum-vapor-evaporation-applied aluminum layer of approximately 1,000 Å is provided on one surface of the resin film, onto which aluminum surface is formed a nonconductive picture image by resin ink of the following composition:

styrenated alkyd resin	1 part by weight
toluene	5 parts by weight

After drying at room temperature the aluminum surface is grounded. Electric charge is applied by a corona charger to which is imposed a DC voltage of +5 kv, thereby depositing positive corona ion on said picture image. The picture image is subsequently developed by a conventional cascade developing system with negatively charged toner to form a toner image on said picture image. The transfer material is then placed onto an image receiving member of a 10mm thick iron plate in such a manner that the toner image surface of the transfer member is held in face-to-face contact with the iron plate. The same kind of rubber magnet as employed in Example I is furthermore superposed on the transfer member. Corona charging is effected from the rubber magnet side in the same manner as in Example I. As a result, the toner image is successfully transferred onto the iron plate which serves as an image receiving member.

EXAMPLE XV

Onto a resin surface of a transfer member employed in Example XIV a magnetic material layer as employed in Example X is applied which magnetic layer is then magnetized by means of an electromagnet. Employing a resin ink as in Example XIV a nonconductive picture image is formed on the aluminum surface and dried to room temperature. Charging and developing steps are carried out as in Example XIV to deposit a toner image on said picture image. The toner image surface is placed in face-to-face contact with a 10mm thick shot-blasted steel plate which comprises the image receiving member resulting in satisfactorily intimate contact therebetween. A corona charging is then carried out to effect image transfer in the same manner as in Example I. Consequently, the toner image is successfully transferred onto the steel plate serving as the image receiving member.

5 A 1mm thick tin-plated steel sheet is having formed thereon a nonconductive picture image in the same manner as in Example XIV as provided. After charging and developing, a toner image is formed onto the picture image. An image receiving member of 100 micron thick triacetylcellulose film is placed onto the steel sheet surface. Over the image receiving film a rubber magnetic sheet is placed as in Example I. The steel sheet is subsequently grounded, and corona charge is applied for image transfer from the rubber magnetic sheet side by a corona charger to which is imposed a DC voltage of -8 kv. As a result the toner image is successfully transferred onto the image receiving member.

10 Although the present examples were specific in terms of conditions and materials used, any of the above listed typical materials may be substituted when suitable in the above examples with similar results. In addition to the steps used to carry out the process of the present invention, other steps may be employed, for example, the image may be negatively charged in which case a charge powder of positive polarity is employed and similarly a corona charge is imposed by a positive voltage. Other materials may be employed for example powder for use in the method of the invention may be colorless or of any desired color. Further, the magnetized magnetic material may be well provided on both the transfer and image receiving members so that they 15 attract each other.

20 Anyone skilled in the art will have other modifications occur to him based on the teachings of the present invention. These modifications are intended to be encompassed within the scope of this invention.

25 35 What is claimed is:

1. A transfer copying process comprising providing a transfer member comprising a nonconductive substrate and a conductive layer provided on one surface thereof, removing said conductive layer in an image-wise pattern thereby exposing grooved nonconductive image areas, embedding toner in said grooved portions to produce an original picture image and transferring the original image to an image receiving member said transferring step comprising applying an electrostatic force between said image transfer member and said image receiving member, uniformly dispersing magnetized magnetic material in at least one of said transferring member or said image receiving member for cooperation with another magnetic material in the other member to effect close contact of a toner image retaining surface of the transfer member with the image receiving member.

2. The process as defined in claim 1 wherein said transfer member comprises a nonconductive substrate and an easily removable conductive layer.

3. The process as defined in claim 2 wherein said nonconductive substrate is selected from a group consisting of polyethylene, polyvinylchloride, polystyrene, polyester, polyvinylidenechloride, and paper impregnated with silicone.

4. The process as defined in claim 1 wherein the conductive layer of said transfer member is selected from the group consisting of conductive particles dispersed in a resin, a vapor evaporated metal film, a plated metal film membrane, and a conductive resin.

5. The process as defined in claim 1 wherein said image receiving member comprises a material selected

13

from the group consisting of copper plate, iron plate, zinc coated iron plate, and tin plated iron plate.

6. The process as defined in claim 1 wherein a magnetized contact plate is superposed over said transfer-

14

ring member so that said transferring member is disposed between said contact plate and said image receiving member.
